Inventor:

Henry E. Meyer,
by Henry E. Meyer, James W. Warner,
Attys.

UNITED STATES PATENT OFFICE.

HENRY E. MEYER, OF DORCHESTER, MASSACHUSETTS.

WINDOW-MANIPULATING IMPLEMENT.

Application filed March 24, 1925. Serial No. 17,906.

To all whom it may concern:

Be it known that I, HENRY E. MEYER, a citizen of the United States, and a resident of Dorchester, in the county of Suffolk and 5 State of Massachusetts, have invented an Improvement in Window-Manipulating Implements, of which the following description, in connection with the accompanying drawings, is a specification, like characters 10 on the drawings representing like parts.

This invention relates to window manipulating implements of the type employed for raising or lowering a window sash and consists in improvements which increase the 15 utility of such devices.

The invention will be best understood by reference to the following description when taken in connection with the accompanying illustration of one specific embodiment 20 thereof, while its scope will be more particularly pointed out in the appended claims.

In the drawings,—

Fig. 1 is a side elevation of a window manipulating implement embodying one form 25 of the invention, the handle thereof being broken away;

Fig. 2 is a side elevation of the implement shown in Fig. 1;

Fig. 3 illustrates some of the uses to which 30 an implement of the type shown in Fig. 1 may be applied in connection with a window equipped with a standard type of window fastening; and

Fig. 4 illustrates the use of the same implement in connection with a window, the sash of which is fitted with a socket for lowering the same.

Referring to the drawings and to the embodiment of the invention which is there submitted for illustrative purposes only, the implement therein disclosed comprises a preferably metallic head 5 having the socket 7 which is adapted to receive the elongated handle 9 in the form of a pole or rod, the handle being fastened in the socket by any suitable means, as by the screw 11. The upper end of the head is provided at one side with a lateral extension 13 constituting 45 a pull member and preferably terminating in a hook-shaped end 15. The pull member is so positioned and shaped as to be usable for pulling down a window sash, the hook member being capable of being inserted in 50 a socketed recess 17 (see Fig. 4), with

which the upper rail of many window sashes are frequently equipped.

Where a window manipulating implement is equipped only with a pull member or other projection of the type described, and it is attempted to raise or lower the sash by engagement directly with the wooden rail of the window, as is apt frequently to be done, the wood is likely to be marred or dented due to the pressure against the 65 wooden rail of the small metallic bearing areas presented by the pull member, and in the course of time the rail is apt to become badly damaged and the window glass scratched or marred, or occasionally broken. 70

For the purpose of conveniently and effectively utilizing the implement to raise or lower the sash by engagement with the sash rail directly, and for other convenience in manipulation, I have herein provided the head with a second lateral offset member 19, preferably at the opposite side from the pull member 13, the offset 19 carrying a flattened metallic face 21, herein rectangular in form, which offset may be also 80 used in manipulating the window. The metallic face 21 of the offset 19 is preferably surfaced with a relatively softer facing 23, which may be of a fibrous or non-abrasive material, and herein comprises a rectangular block of rubber screwed to the metallic face 21, providing a relatively soft face overlying the walls of the face 21. This provides a member the face of which is adapted 85 to bear against a window pane without damage thereto, while the ends thereof may be utilized to press against the wooden rail of the window sash also without damage to the woodwork. For convenience in manipulation, as will be apparent from Figs. 3 and 90 4, the face of the bearing member 23 is offset at a slight angle to the axis of the handle.

The utility of the described form of implement will be understood from an inspection of Figs. 3 and 4. In Fig. 3 I have 100 shown the lower rail 25 of an upper window sash 27 and the upper rail of a lower window sash 31, the window being equipped with a well-known type of window lock comprising the latch carrying member 33 and 105 the lock member 35 which are fastened by snapping down the swinging latch lever 37 from the dotted to the full line position therein shown.

To lock the fastening, the pull member is 110

engaged with the back of the latch lever and the implement pulled to throw the latch lever down into the full line locking position. To unlock the window the implement is reversed, the upper edge of the bearing member 23 being pushed up against the overlying tip of the latch lever to snap the latter into its upright or unlocked position. The window sash may then be raised by 10 lowering the implement to place the face of the bearing member against the window pane, after which it is moved up until its upper edge bears against the underside of the window rail, whereupon a lifting pressure may be exerted against the rail to raise the sash without danger of any damage either to the rail or to the window pane. If desired, the sash may be lowered by pulling down on the handle with the lower edge of 15 the bearing member resting against the upper side of the window rail.

In manipulating the upper sash, the latter may be lowered as indicated in full lines in Fig. 4 by inserting the pull member in 20 the socket 17 and pulling down the sash. On the other hand, the sash may be raised without damage either to the window pane or the wooden rail by reversing the head, causing the bearing member to engage the 25 window pane and pushing up with the same against the sash rail. It will thus be seen that the described form of implement may be utilized conveniently to perform all the operations of raising or lowering either the 30 lower or upper sash without the likelihood of damage thereto which has heretofore accompanied such manipulation.

While I have herein shown and described 40 for the purpose of illustration one specific embodiment of the invention, it is to be understood that extensive deviations may be made from the mechanical construction and the form and relative arrangement of parts herein described, all without departing from 45 the spirit thereof.

Claims:

1. A window manipulating implement comprising a head having a socket adapted 50 to receive an elongated handle or pole, said head being provided at one side with a laterally extending, hook-shaped, pull member, and at the opposite side with a lateral offset provided with a face adapted to bear

against the window pane and simultaneously exert a lifting pressure against the underside of the upper rail of the window sash to raise the same, the face of said offset being inclined at an angle to the axis of the handle and said offset comprising a flattened metallic head provided with a non-metallic covering of rubber for its window 55 engaging walls.

2. A window manipulating implement comprising a head provided at one side with a laterally extending pull member and at 60 the opposite side with a non-metallic, laterally offset, bearing member provided with a face presenting a substantial bearing area adapted to bear against the window pane, and lateral edges also presenting a substantial bearing area to engage the rail of the window sash.

3. A window manipulating implement comprising a head provided at one side with a laterally extending pull member and a 65 laterally extending push member having a bearing face adapted to engage the window pane, and bearing edges also presenting a substantial bearing area simultaneously to bear against the rail.

4. A window manipulating implement having a laterally extending member presenting to the window pane an extended bearing area and also having an edge adapted simultaneously to bear against the rail 75 of the sash, said bearing area and edge being faced with a non-abrasive material.

5. A window manipulating implement comprising a head adapted to be secured to a handle, a lateral offset providing a support for the bearing member having a bearing face of extended area adapted to bear against the window pane, and an edge adapted to engage the rail of the sash, said 80 face being inclined to the handle axis.

6. A window manipulating implement having a head adapted to be secured to a handle, and a lateral offset comprising a metallic support for a bearing member and having a non-metallic bearing face of extended area adapted to rest against the window pane and simultaneously engage the 85 window rail.

In testimony whereof, I have signed my name to this specification.

HENRY E. MEYER.
